UNITED STATES PATENT OFFICE

GUSTAVE O. DEGENER, OF NEW YORK, N. Y., ASSIGNOR TO ROYAL TYPEWRITER COMPANY, INC., OF NEW YORK, N. Y., A CORPORATION OF NEW YORK

TYPEWRITING MACHINE

Application filed December 12, 1927. Serial No. 239,491.

The invention claimed herein relates to means for operating the ribbon vibrator which is particularly adapted for use in power driven machines such for example as that shown in my application Ser. No. 243,063, filed Dec. 28, 1927. It may however with but little or no change in the construction and without any change whatever in the principle be applied to other types of power operated typewriting machines.

In the drawing the figure represents a side elevation of the parts composing the present invention with certain parts in fore and aft section.

15 The invention is illustrated as embodied in the usual standard Royal machine having a platen A, type bars B, type guide C, and ribbon vibrator D. It may, however, be applied to typewriting machines of other 20 character so far as these elements are concerned.

The key levers 1 are fulcrumed on an axis 2 and are normally held against a stop 3 by a spring, not shown. The type bars B are 25 connected with power levers 4 by any suitable intermediate connections, such as shown in my other application above referred to. The power levers 4 are fulcrumed on an axis 5 and each one has pivotally mounted thereon near its rear end a star wheel 6 which 30 cooperates with a rotating or power shaft 7. This specific construction and the means by which the power levers are given a sudden movement from the position shown in full 35 lines to that shown in dotted lines, is fully set forth in my above mentioned application and forms no part of the present invention except in combination with the ribbon vibrator. The star wheel 6 is pivoted to the 40 power lever and includes extensions provided in their ends with depressions adapted to fit the ends of the fingers formed on the power shaft 7. The key 1 cooperates with the power lever 4 to normally retain the star 45 wheel extensions out of contact with the fingers of the power shaft. A spring 8 is connected to each power lever and to a plate 9 carried by a transverse member 10 and 50 these springs normally hold the power levers

in their position of rest, as shown in the drawings.

Each key lever has a downwardly extending portion 2^a, and a flat spring 2^b carried by the key lever has a horizontal portion 2^c so arranged as to form a recess Y between the spring and the portion 2^a of the key lever. The front end of each power lever 4 has a bent extension 4^a, the front face of which is adapted to contact with the rear 55 edge of the horizontal portion of the spring 2^b while the upper edge of this extension is adapted to contact with the lower edge of the downwardly extending portion 2^a of the key lever. Associated with the star wheel 6 is a flat spring 6^a which holds the star wheel against accidental displacement but permits its rotation relative to the power lever. The star wheel is provided with arms 6^b having depressions 6^c in their outer ends. 60 These depressions are adapted to receive the ends of the fingers 7^a on the power shaft 7. The ends of these fingers are formed in the arcs of the circle concentric with the axis of the shaft.

A universal bar 11 carried by a rock shaft 12 underlies all of the power levers 4 and this rock shaft has an upwardly extending arm 13 which is connected by a link 14 with a lever 15 near the rear of the machine which 75 is pivoted on a shaft 16. A spring 17 connects the upper end of this lever with an offstanding lever 18 also carried on said shaft 16. Projections 19 from the two levers 15 and 18 limit their movement toward each 80 other under the influence of the spring 17.

The upper end of the lever 18 has a pin 20 which lies in position to engage and operate the usual actuator 21 for the ribbon vibrator. The ribbon vibrator D is connected to a bell crank lever pivoted to turn on an axis 23 and retained in normal position by a spring 24. The downward extending arm 25 of said bell crank lever is pivotally connected at 26 to the actuator 21 intermediate its ends. An arm 27 on said actuator engages the usual cam member 28 by which the parts are moved to different position when a multicolored ribbon is to be employed.

When a type key lever is depressed the rear end of the power lever 4 will drop slightly and the star wheel will come in contact with the rotating member 7. Consequently upward movement will be given to the rear end of the power lever and corresponding movement to the front end of the lever as shown in the dotted line position. This movement will move the universal bar 11 to dotted line position and exert a forward pull on the link 14. In power operated constructions of this character this forward pull is very sudden and sharp and the present construction employs the spring 17 in order to cushion the movement and avoid such jerks or strains upon the mechanism as well as consequent noise. The spring 17 will yield slightly but will transmit movement to the lever 18 which through the mechanism described will operate the ribbon vibrator.

The usual universal frame 29 is provided which is operated from the type bars by means of the links 30. In the ordinary machine, this universal bar operates the ribbon mechanism but in the present case it is so formed that it does not come in contact with the actuator 21. It operates the escapement mechanism in the old and well known manner.

It will be apparent that the invention disclosed comprises a means for operating the ribbon vibrator which is especially adapted for use in a power machine and which can be embodied therein with but little modification of the existing construction. The provision of a spring in the operative connections also lessens the noise and prevents any undue strain being placed upon the connections and assist in a rapid and efficient operation.

The movement generated by the power shaft is greater than the movement required to elevate the ribbon, therefore the spring 17 by yielding compensates for the excessive movement, thereby retaining the ribbon elevated a correspondingly longer period of time.

Assuming that the parts are in the normal position shown in the drawings, a slight depression of the key lever 1 will move the spring 2^b and allow the extension 4^a on the power lever 4 to move into the recess Y. This allows an upward movement of the front end of the power lever under the influence of the spring 8. The upward movement of the power lever will cause a corresponding downward movement of the rear end of said lever. The ends of the fingers 7^a of the power shaft will engage the depressions 6^c in the arms 6^b of the star wheel and thereby quickly raise the rear end of the power lever and consequently effect operation of the ribbon vibrator.

The invention may of course be embodied in different machines and minor changes

may accordingly be made without in any way departing from the spirit of the invention which is to be regarded as limited only by scope of the appended claims.

I claim as my invention:

1. In a typewriting machine, a ribbon vibrator, an actuator therefor, a power operated lever, a universal bar actuated thereby, and connections between the universal bar and the actuator which include two levers and means yieldingly connecting the same. 70

2. In a typewriting machine, a ribbon vibrator, an actuator therefor, a power operated lever, a universal bar actuated thereby, and connections between the universal bar and the actuator which include two levers pivoted on a common axis, a spring connecting said levers, and means for limiting the movement of the levers toward each other under the influence of the spring. 80

3. In a typewriting machine, a ribbon vibrator, an actuator therefor, a power operated lever, a universal bar actuated thereby, and connections between the universal bar and the actuator which include two levers pivoted on a common axis, a spring connecting said levers intermediate their ends, a link connected to one lever and to the universal bar, and means on the other lever adapted to engage the actuator. 90

4. In a typewriting machine, a ribbon vibrator, an actuator therefor, a power operated lever, a universal bar actuated thereby, an upstanding arm on the universal bar, two levers pivoted on a common axis, a link connecting said arm to one of said levers, a spring normally drawing said levers toward each other, and means on the other lever adapted to engage the actuator when the power lever is operated. 100

5. In a typewriting machine, the combination with a ribbon vibrator, of an actuator therefor, a power lever, connections between the power lever and the actuator for operating the vibrator upon movement of said power lever, a power shaft having fingers with ends formed in the arcs of a circle concentric with the axis of the shaft, a star wheel pivoted to said power lever, the arms of said star wheel being provided in their ends with depressions adapted to fit the ends of said fingers and thereby move said power lever to operate the vibrator, and a key for controlling said power lever to effect operative engagement of the star wheel arms with the fingers on the power shaft. 110

6. In a typewriting machine, the combination with a ribbon vibrator, of an actuator therefor, a power lever, connections between the power lever and the actuator for operating the vibrator upon movement of said power lever, a power shaft having fingers with ends formed in the arcs of a circle concentric with the axis of the shaft, a star 120

wheel pivoted to said power lever, the arms of said star wheel being provided in their ends with depressions adapted to fit the ends of said fingers and thereby move said power lever to operate the vibrator, and a key for controlling said power lever to effect operative engagement of the star wheel arms with the fingers on the power shaft, said power lever and key being normally engaged to retain the star wheel arms of the power lever out of contact with the fingers of the power shaft.

In testimony whereof, I have hereunto subscribed my name.
